Primary Examiner — Philip S Hyder*Assistant Examiner* — Ramzi Almatrahi(74) *Attorney, Agent, or Firm* — Klarquist Sparkman, LLP(57) **CLAIM**

I claim the ornamental design for a dome camera, as shown and described.

DESCRIPTION

FIG. 1 is a bottom perspective view of a dome camera showing my new design;

FIG. 2 is a bottom plan view thereof;

FIG. 3 is a top plan view thereof;

FIG. 4 is a right side elevation view thereof;

FIG. 5 is a left side elevation view thereof;

FIG. 6 is a front elevation view thereof; and,

FIG. 7 is a back elevation view thereof.

The broken lines depict portions of the dome camera in which the design is embodied that form no part of the claimed design.
